(57) **CLAIM**

The ornamental design for an analytical test card, as shown and described.

DESCRIPTION

FIG. 1 is a front view of a analytical test card of our new design;

FIG. 2 is a rear view thereof;

FIG. 3 is a perspective view showing the top and front thereof;

FIG. 4 is a perspective view showing the top and rear thereof;

FIG. 5 is a left side perspective view of the analytical test card with the left side of the card bent into a curvature, showing the left side and rear thereof;

FIG. 6 is a right side perspective view of the analytical test card with the left side of the card bent into a curvature, showing the right side and rear thereof; and,

FIG. 7 is a left side end view showing the left side and front thereof.

The trademarked portions forming part of the claimed design are a registered trademark of Orion Diagnostica Oy, Koivu-Maankaantie 6B, FI-002200 Espoo, Finland.
